UNITED STATES PATENT OFFICE.

MARTIN H. REYMOND, OF BINGHAMTON, NEW YORK.

PROCESS OF GAUGING LEATHER.

Application filed August 11, 1921. Serial No. 491,633.

To all whom it may concern:

Be it known that I, MARTIN H. REYMOND, a citizen of the United States, residing at Binghamton, in the county of Broome and 5 State of New York, have invented a certain new and useful Process of Gauging Leather, of which the following is a specification.

This invention relates to measuring the cutting value of leather in advance of cutting. More particularly, it relates to definitely predetermining the effect on the cutting value of the many variables that exists in leather, such as size of hide, shape of hide, 10 raggedness of edge, tears, surface marks, brands, scars, grubs, cuts, creases, holes, grain texture, body texture, thickness, grain imperfections, color imperfections, finish imperfections, etc.

The principal object of this invention is to 20 provide a convenient and economical process for definitely predetermining for any given supply of leather, for a given purpose, what its cutting value is compared to any other given supply of leather, taking into account 25 the above mentioned variables.

Another object is to provide a particular form of apparatus whereby this process may be advantageously carried out.

It would of course be possible to predetermine what a given supply of leather 30 would cut for by laying off on the surface the product it is intended to cut from it. But this would not only involve a prohibitive amount of labor, but would not be definite in 35 that the varying human skill of the man doing the laying out would give varying results.

Previous to this invention, where any attempt has been made to predetermine the cutting 40 quality of leather on a practical scale, this has been done by a general appraisal and sorting process. This usually consists of classifying each hide as grade No. 1, No. 2, No. 3, etc. by a glance over its surface, 45 whereupon it is thrown upon a No. 1, No. 2, No. 3, etc. pile respectively. This gives very unreliable results. No two sorters will sort exactly alike, the human equation being a large factor. Nor will the same sorter sort 50 alike on different occasions. For example, given poor leather to sort, his No. 1 leather will usually be a poorer grade than when sorting better leather. Further, not only is such sorting unreliable, but the segregation 55 of good leather from poor leather often results in less economical cutting. For exam-

ple, in the cutting of shoes, the cutters receiving the better end of the leather have an excess of clean leather which they must cut up into small parts such as tips, stays, 60 etc. which they could just as well have obtained from poorer stock. On the other hand the cutters receiving the poorer end of the leather, in order to get the required number of large shoe parts, must use an excessive amount of leather, leaving a lot of available small part stock unutilized. 65

In contrast with the previous state of the art such as described, I attain the object of my invention, the determination of the comparative cutting quality of any supply leather, without sorting, and without needing any knowledge of the product to be cut beyond knowing what imperfections, if any, may satisfactorily appear in the finished 70 product. Further, the human equation is eliminated in the result, the process being governed throughout by absolutely rigid conditions. 75

In general terms the process consists of: 80 indicating over the surface of the leather small equal-sized equally-spaced areas; inspecting these small areas individually to determine whether they contain in any portion of their scope any imperfections such 85 as previously mentioned which are not allowable in the finished product; counting the number of such small areas which contain no such imperfections; and, from the ratio of this number of small areas to the 90 total area of the leather they were obtained from, obtaining a measure of the cutting quality of the leather, or what may be termed the quality number of the leather. 95

The accompanying drawing illustrates a 95 particular application of this process. Figure 1 is a plan view of the apparatus, and Figure 2 is a side view. Similar numerals in the two views refer to similar parts.

The leather to be gauged 1, is shown partially intercepted between cylinder 2 and flexible perforated band 3. This band is perforated with equal-sized holes at equal distances over its surface, as shown. The man doing the grading stands at the front 100 of cylinder 2 to inspect the various small areas. The arrow 4 indicates his approximate angle of vision. After he has inspected the areas he can conveniently see, he turns the two cylinders 2 and 5, together with band 105 3, and leather 1, by means of wheel 6, bringing the next region of small areas into con- 110

venient inspection position. The cylinder 2 has a soft rubber exterior 7, which serves two purposes. In the first place, it causes leather 1 to be snugly pressed against band 3 at 5 every point, and in the second place it permits bending in the leather to aid in detecting spongy portions.

Assuming that upon inspection by this method, the following observations were obtained for the piece of leather 1:

Number of whole areas containing no imperfections not allowable in the product ..... A

15 Total area of the piece of leather 1. F sq. ft.

The quality number of the leather would be A/F .

This quality number, however, in order to be in preferred form, would be varied 20 slightly so as to always range between the extremes of .00 and 1.00. This will be the case if the total area F is expressed in units of the same size as the area represented by the holes in band 3. For example, if the 25 band 3 contains one hole to every half square foot of surface, the total area of leather, would have to be expressed in half square feet, and would be $2XF$. This would make the quality number $A/2XF$.

30 If the area of the leather is not otherwise available, it may be obtained by counting the number of imperfect circles and the number of partial circles as well as the number of perfect circles. Thus:

35 Let number of perfect circles = A.

Let number of imperfect circles = B.

Let number of partial circles = C.

40 The partial circles will average to half a circle each and the quality number will be:

$$\frac{A}{A+B+C/2}$$

which will be the same value as if determined as described in the directly preceding paragraph,

$$\frac{A}{A+B+\frac{C}{2}}$$

45 This quality number may be obtained for an individual piece of leather or for a pile of hides. The larger the amount of leather inspected the more accurate this quality number will be, the errors balancing out according to the law of averages. For any 50 considerable quantity of leather, the possible error is negligible. There will be no appreciable variation in quality numbers obtained from successive gaugings on the 55 same lot of leather.

60 A better understanding of the above described quality number may be obtained by considering it from a slightly different viewpoint. Assume a given quantity of 65 leather of known quality number. Imagine

this leather to be cut up into small squares of the same area as the circles in band 3. Now suppose these squares are inspected for imperfections which may not appear in the product. Suppose the squares containing no such imperfections are sorted into one pile, and counted. Now suppose the ratio of the total area of these parts to the total area of the original leather is determined. This result will be identical with the quality number previously obtained. Thus, what is done in determining the quality number of leather is to determine, without actually cutting the leather, what the utilization would be if it were cut up mechanically under certain specific conditions, instead of in the usual manner of working around imperfections. While the cutting quality of the leather as actually cut, i. e. working around imperfections, does not 75 vary directly with this quality number, it bears a certain relation to it. This relation may be determined by experiment for any given set of conditions, such as size of holes used in band 3, shape and size of pattern to 80 be cut, kind of leather to be cut, etc.

Holes in band 3 should preferably be of a size comparable with the size of the parts to be cut, although no very close ratio need be adhered to. For example, a $\frac{1}{4}$ square 95 foot hole may be used to gauge leather for cutting into parts which are only $\frac{1}{8}$ square foot in area without causing any large error.

It should be noted that considerable modifications are possible in the round, equal-sized, equally-spaced small areas shown in the drawing. Areas of different shape and differently spaced might be used. It would also be possible to use more than one size 100 of area; for example, alternate larger and smaller areas might be used. The only basic requirement is that they be regular in order of size and shape, and in spacing. The use of round areas of equal size and 105 equally spaced is, however, a preferred form. In the first place defects are more readily observed in a figure containing no corners, the circle being the simplest figure 110 of that kind. In the second place the spacing shown, where only part of the surface is visible, is of advantage in making each small area a segregated unit in as far as inspection is concerned, eliminating the 115 psychological effect sometimes obtained in inspecting two directly adjacent areas of 120 imagining the extension in prohibitive degree of a defect existing in one of these areas into the other. In the third place the inspection of only half of the surface 125 reduces the work of inspection about one half, at the same time giving sufficiently accurate results for practical purposes. In the fourth place the inspection of only a part of the surface makes possible a simpler 130

mechanical design of apparatus for indicating the desired areas on the leather than if the entire surface had to be inspected.

A further use of this process exists, where 5 parts of two different qualities are cut from the same leather, in indicating what proportion of first quality and second quality parts should be produced. For example, assume that two qualities of shoes, each with definite 10 requirements from the standpoint of allowable imperfections of the many kinds mentioned in the early part of this specification, are to be cut from a given supply of leather. Equal-sized, equally-spaced areas 15 are indicated over the surface. These areas are inspected as to whether they contain any imperfections not allowable in first quality shoes, and those which do are inspected as to whether they contain any imperfections 20 not allowable in second quality shoes. The number of areas suitable to each quality of shoes is counted. The relative proportion of these two quantities provides an index number as to the proportion of first 25 and second quality parts which should be obtained.

While the particular processes described very well illustrate both the principle and uses of this invention, the full scope of the 30 invention has more fully and concisely been embodied in the appended claims.

I claim as my invention:

1. The process of measuring the cutting quality of leather, consisting of indicating 35 over its surface regularly-spaced areas of regular size and regular shape, inspecting these areas individually to determine which do not contain any imperfections not allowable in a product of fixed standard that may 40 be cut from said leather, counting the number of such areas, and computing the ratio of this number of areas with the total area of said leather.

2. The process of determining the cutting 45 quality of a given supply of leather in the form of a quality number, consisting of indicating over the surface of the leather equal-sized equally-spaced areas, inspecting these areas individually to determine which 50 do not contain any imperfections not allowable in the product to be cut, counting the number of such areas, and computing the ratio of this number of areas to the total area of said given supply of leather.

55 3. The process of determining the cutting quality of a given supply of leather of unknown area in the form of a quality number, consisting of indicating over the surface of the leather equal-sized equally-spaced areas, inspecting these areas individually to determine which do not contain any imperfections not allowable in the product to be cut, counting the number of such areas, counting the number of areas which 60 do contain such imperfections, counting the

number of partial areas, and computing the ratio of the number of areas containing no such imperfections to the sum of the areas containing no such imperfections the areas containing such imperfections and half the 70 partial areas.

4. The process of determining the cutting quality of a given supply of leather in the form of a quality number, consisting of inserting it under a screen perforated with 75 equal-sized equally-spaced areas, inspecting individually through said perforations the areas thus indicated over the surface of the leather to determine which do not contain any imperfections not allowable in the product to be cut, counting the number of such areas, and computing the ratio of this number of areas to the total area of said given supply of leather.

5. The process of determining the cutting 80 quality of a given supply of leather in the form of a quality number, consisting of indicating over the surface of the leather round equal-sized equally-spaced areas, inspecting these areas individually to determine which 85 do not contain any imperfections not allowable in the product to be cut, counting the number of such areas, and computing the ratio of this number of areas to the total area of said given supply of leather.

6. The process of determining the cutting 90 quality of a given supply of leather in the form of a quality number, consisting of inserting the leather between an elastic surface and a screen perforated with round 100 equal-sized equally-spaced holes, inspecting individually the small round areas thus indicated over the surface of the leather to determine which do not contain any imperfections not allowable in the product to be cut, counting 105 the number of such areas, and computing the ratio of this number of areas to the total area of said given supply of leather.

7. The process of determining the cutting 110 quality of a given supply of leather in the form of a quality number, consisting of inserting it between a cylinder and a flexible band, perforated with round equal-sized 115 equally-spaced holes, inspecting individually the small round areas thus indicated over the surface of the leather to determine which do not contain any imperfections not allowable in the product to be cut, counting the number of such areas, and computing the ratio of this number of areas to the total 120 area of said given supply of leather.

8. The process of determining in the form of an index number the relative proportion of two products of different quality requirements to be cut from a given supply of 125 leather, consisting of indicating over the surface of the leather equal-sized equally-spaced areas, inspecting these areas individually to determine which do not contain any imperfections not allowable in the first 130

quality product, inspecting those areas which do contain such imperfections to determine which do not contain any imperfections not allowable in the second quality product, counting the number of areas entirely suitable to the first quality product, counting the number of areas not entirely suitable to the first quality product but entirely suitable to the second quality product, and computing the ratio of said number of first quality areas and said number of second quality areas.

9. The process of measuring the cutting

quality of leather, consisting of indicating over its surface regularly spaced areas of equal size and similar shape, inspecting these areas individually to determine which come up to some fixed standard as to imperfections allowable therein, counting the number of such areas that come up to such standard, and computing the ratio of this number of areas with the total area of said leather.

August 9, 1921.

MARTIN H. REYMOND.
